FIG. 1 is a front view in solid lines of a modular unit for grille panels, showing my new design.

FIG. 2 is a side view thereof.

FIG. 3 is a top plan view thereof.

FIG. 4 is a perspective view of a modular unit as seen from the rear of FIG. 1 and also as viewed from the left-hand side of FIG. 2.

The broken lines in FIG. 1 showing a plurality of modular units are disclosed for illustrative purposes only.

I claim:

The ornamental design for a modular unit for grille panels, substantially as shown and described.
